UNITED STATES PATENT OFFICE.

JOHN DAVIDSON, OF PENDLETON, AND WILLIAM OLIVER LARMUTH, OF SALFORD,
ENGLAND.

UNIDIRECTIONAL-FLOW STEAM-ENGINE.

1,112,985.

Specification of Letters Patent.

Patented Oct. 6, 1914.

Application filed October 5, 1912. Serial No. 724,129.

To all whom it may concern:

Be it known that we, JOHN DAVIDSON and WILLIAM OLIVER LARMUTH, subjects of the King of Great Britain, residing at Pendleton and Salford, respectively, both in the county of Lancaster, England, have invented certain new and useful Improvements in and Connected with Unidirectional-Flow Steam-Engines; and we do hereby declare 10 the following to be a full, clear, and exact description of the invention, such as will enable others skilled in the art to which it appertains to make and use the same.

Our invention relates to improvements 15 in and connected with uni-directional flow steam engines in which means are provided for taking steam from the engine for heating and other auxiliary purposes after it has expanded in the usual way to some pre- 20 determined pressure. Hitherto such means consisted of valves opened automatically by the steam and allowing the escape of a fixed quantity of steam from the cylinder after a certain amount of expansion has 25 taken place.

The object of our invention is to provide 30 means, whereby the amount of steam taken from the cylinder can be varied automatically to suit requirements, and whereby the 35 engine may be run as an ordinary condensing engine under most economical conditions, when steam for heating purposes and the like is not required. We attain these objects by the mechanism illustrated in the accompanying two sheets of drawing, in which:

Figure 1 is a part sectional front view and Fig. 2 a side view showing an embodiment 40 of our invention. Fig. 3 is a detached plan. Fig. 4 is a sectional front view and Fig. 5 a part sectional side view of a second embodiment of our invention.

Similar letters refer to similar parts throughout the several views.

45 Referring to the figures generally, we provide opposite the steam admission valves a , a two piston valves b , b , which act as auxiliary valves and are secured to a rod c , which is connected up to an eccentric c' on the crank 50 shaft of the engine (not shown). The piston valves b , b are provided with inclined slots d which normally correspond with similar slots e in the valve linings f . Two ports g lead from the slots in valve linings f 55 to the cylinder h of the engine. The steam

leaves the slots in the valve linings f by the pipe i which leads into the exhaust pipe or to any desired place.

The valves b , b may be turned by the following mechanism:—The valve rod c is 60 slidably connected to one end of an arm k which is pivotally connected at its other end to a piston rod l , the piston m of which works in a relay cylinder n and is actuated by oil, steam, water or the like under pressure. This motive fluid is controlled by a slide valve o connected by a link p to a straight lever q pivoted on a lever r . The lever q is connected to one arm of a bell-crank lever s by a link t . The lever r is pivoted at one end to a fixed bracket and at the other to an arm u linked to the piston rod l and fulcrumed on the engine body. The second arm of the lever s is connected to a piston rod v the piston w of which is under 75 the influence of a spring x . The cylinder y of the piston w is connected by a pipe z to the auxiliary main. The parts are so arranged that when the engine is working under ordinary conditions, the piston w will 80 be in the center of its travel.

The operation of the means described is as follows:—Steam admitted in the usual way is expanded until a predetermined point is reached at which the auxiliary valves b , b will be opened by the eccentric c' and allow the steam to escape until another predetermined point is reached, when the auxiliary valves b , b , will be closed; expansion 85 will be then continued in the cylinder h 90 and the remainder of the steam exhausted in the usual way.

The period of opening the auxiliary valves b , b as previously stated will be regulated to suit circumstances and varied automatically by the pressure in the auxiliary steam main, acting upon the described mechanism. For example, if the pressure falls in the said auxiliary main, the piston w will 100 be moved by the spring x and the motive fluid thereby admitted to one side of the piston w and move the same, this movement being transmitted to the valve rod c , which is turned, and causes the slots d and e to be correspondingly displaced in relation to each other. The valves b , b will then 105 allow more steam to enter the mains. If the pressure in the auxiliary main increases, the piston w will be moved in the opposite direction, and the valves b , b so moved there- 110

by as to allow less steam to enter the said mains.

When steam is not required for heating or other auxiliary purposes, the piston valves *b, b* will not open at all and the engine will run as an ordinary engine. According to the amount of steam required, the engine governor will regulate the amount admitted to the engine in the well known manner, so 10 that it will be capable of doing the work required although a large quantity of steam is taken out of the cylinder for auxiliary or other purposes.

The means described permit of running 15 the engine always under economical conditions and yet automatically and economically supplying steam when required after it has done work in the engine for auxiliary purposes.

20 We may also attain the object of our invention by using ordinary piston valves in lieu of the hereinbefore described angular ported valves, and regulating the time of opening by means of a variable eccentric 25 controlled by similar means as those described for turning the said angular ported valves. Figs. 4 and 5 show an arrangement of this kind, in which 2 are the piston valves actuated by the variable eccentric 3, which 30 may be of any suitable construction. For example the same may consist of an eccentric disk 4 having a slot 5 in which is situated a block 6 on the crank shaft 7 of the engine. The block 6 is provided with 35 transverse keys 8 which slide in slots in the eccentric disk 4 which is prevented from sliding by its strap and rod connected to the guided rod 6, and two arms 9 rigidly connected to a sleeve 10 on the shaft 7. The 40 sleeve is moved longitudinally by means of a ring 11 rotatable on the same and a lever 12 connected to the ring 11. The extent of the movement of the piston valves 2 is regulated by means of the relay cylinder *n* the 45 piston rod *l* of which is connected to the lever 12, and actuates the same, thereby moving the block 6 and its transverse keys 8 the latter causing the eccentric disk to be moved at right angles to the crank shaft 7 50 and change its degree of eccentricity. The movement of the relay cylinder piston is obtained and controlled by the same means and in the same manner as described with reference to Figs. 1, 2, and 3.

We claim:—

1. In a uni-directional flow steam engine, 55 an auxiliary exhaust port in each extremity of the working cylinder, valve casings with openings communicating with the said exhaust ports, an auxiliary exhaust pipe independent from the main exhaust pipe in open communication with the said valve casings for supplying steam for auxiliary purposes, and a mechanically and positively actuated valve in each of the said casings 60 with variable movement in relation to the said openings, for opening and closing the said openings to a variable extent during the working stroke of the piston and before the central exhaust ports are opened, for the 70 purpose of varying the amount of steam passing during the working stroke through the said auxiliary exhaust ports in accordance with the momentary requirements and irrespective of the momentary pressure existing in the working cylinder.

2. In a uni-directional flow steam engine, 75 an auxiliary exhaust port in each extremity of the working cylinder, valve casings with openings communicating with the said exhaust ports, an auxiliary exhaust pipe independent from the main exhaust pipe in open communication with the said valve casings for supplying steam for auxiliary purposes, and a valve in each of the said 80 casings operatively connected to the crank shaft of the engine and with a movement in relation to the openings to the said valve casing, varying in accordance with the pressure momentarily existing in the said auxiliary exhaust pipe, for opening and closing the said openings to a variable extent during the working stroke of the piston and before the central exhaust ports are opened, for the purpose of varying the amount of 85 steam passing during the working stroke through the said auxiliary exhaust ports in accordance with the momentary requirements and irrespective of the momentary pressure existing in the working cylinder. 90

100 In testimony whereof we have affixed our signatures in presence of two witnesses.

JOHN DAVIDSON.

WILLIAM OLIVER LARMUTH.
